UNITED STATES PATENT OFFICE.

FORREST W. MANKER, OF JACKSON HEIGHTS, NEW YORK, ASSIGNOR TO SURFACE COMBUSTION COMPANY, OF NEW YORK, N. Y., A CORPORATION OF NEW YORK.

ENAMELING FURNACE AND METHOD OF PREPARING THE SAME.

Application filed February 3, 1926. Serial No. 85,649.

This invention relates to improvements in furnaces and a method of preparing the same and more particularly to furnaces in which bath tubs may be heated during the 5 enameling operation.

The most common type of furnace for use in enameling bath tubs is the muffle type furnace adapted to be heated by such fuels as coal, oil or producer gas. The muffle furnace is, however, expensive to build and to 10 keep in repair though it has the advantage of giving a working chamber atmosphere that is practically free of dust and the like which cause specks and imperfections in the 15 enamel.

The present invention has for its objects to provide a furnace for the purpose specified which shall be of the direct-fired type and in which gaseous fuel may be utilized 20 for heating purposes; which shall be economical to build and keep in repair; to provide a furnace in which the tubs may be quickly and uniformly heated without danger of overheating the rims of the tubs and 25 to provide a furnace in which the danger of particles falling into the tub from the walls and roof of the furnace shall be reduced to a minimum.

In accordance with the present invention 30 the heating chamber of the furnace is formed with side walls which diverge upwardly from the floor of the heating chamber, the angle of inclination of the side walls preferably being about the same as that of the side walls 35 of the standard conventional type of bath tub. The floor of the heating chamber is a relatively thin false floor beneath which gaseous fuel is adapted to be burned to heat 40 the floor whereby portions of the tub may be heated by heat radiating from the floor. This floor is provided with openings along 45 the side walls of the chamber which openings serve as passages through which the combustion gases may pass upwardly into the heating chamber for circulation about the tub to further heat the same.

The roof of the heating chamber is preferably of arched form and is provided with a longitudinally extending row of openings 50 through which the combusted gases may pass out of the heating chamber. Associated with the openings are means for controlling the relative sides thereof in order to insure the proper circulation of the gases at the ends

of the heating chamber and to maintain a 55 uniform temperature within the same.

The heating chamber is fired by gaseous fuel introduced below the floor of the heating chamber. To enable utilization of the residual heat in the gases leaving the heating chamber through the roof openings, a recuperator is mounted on the top of the furnace whereby the hot gases leaving the heating chamber pass directly to the recuperator to preheat the air which is to be mixed 60 with the fuel gas before its introduction into the combustion space beneath the floor of the heating chamber.

To prevent particles of brick and the like from breaking away from the roof and walls 70 of the heating chamber and falling into the enamel on the tub, the interior surface of the chamber is glazed with a suitable refractory glaze.

The above and other various novel features of the invention will more fully appear from the detailed description taken in connection with the accompanying drawings forming part of this specification and will be 75 particularly set forth in the appended claims. 80

Referring to the drawings:

Fig. 1 is a vertical transverse section through the improved furnace and showing the preferred construction thereof;

Fig. 2 is a horizontal section through the 85 furnace on a reduced scale, the floor of the heating chamber being shown in plan, and

Fig. 3 is a vertical section through the furnace on the same scale as Fig. 2.

The base on which the furnace rests is indicated at 10; the exterior side walls of the furnace at 12 and the end walls thereof at 14. One of the end walls is provided with a door opening 16 through which the work to be heated may be entered into the furnace 90 and removed therefrom. Associated with the door opening is a door 18 which is preferably of the vertically movable type, suitable upright guides 20 being provided in the wall for confining the door in place. 100 The weight of the door is balanced by suitable counter-weights 22 located at the opposite end of the furnace and which are connected to the door by suitable cables 24 which pass over the top of the furnace and 105 around suitable pulleys 26 mounted on said top. The door is opened and closed by means of a suitable motor 28 disposed in a

pit below the door, a suitable cable 30 leading from the motor to the bottom of the door. The door in opening preferably moves downward whereby to minimize the entrance of dust into the furnace, more particularly such dust which but for the downward movement of the door would be drawn into the furnace by the draft.

The heating chamber with which this invention is more particularly concerned has an arched roof 32, a relatively thin flat floor 34 which is of less width than the width of the roof of the chamber, and upwardly diverging side walls 36.

15 The floor 34 is a false floor which is supported in spaced relation with respect to the base 10 of the furnace by means of a series of pillars 38. The floor is provided with a series of openings 40 which extend along the 20 foot of each of the inclined side walls 36, the openings along one inclined wall being in staggered relation with respect to the openings along the other inclined wall for a purpose that will presently appear. The floor 25 openings 40 serve as passages through which hot gases may enter the heating chamber, these hot gases constituting the products of combustion formed by the burning of fuel beneath the floor of the heating chamber as 30 will be presently explained.

The arched roof 32 of the heating chamber is provided with a row of openings 42 through which the gases entering into the furnace may leave the same. These roof 35 openings are preferably located in a line which extends longitudinally of the roof along the middle thereof. In order to control the outflow of the gases and the circulation thereof within the heating chamber 40 there is preferably associated with the roof openings movable tiles 44 by means of which the size of the openings can be varied or by means of which some of the openings can be closed. The roof openings 42 open into a 45 longitudinally extending passage or manifold 46 from whence the gases flow to a recuperator generally indicated at 48.

Gaseous fuel is introduced and burned beneath the floor of the heating chamber 50 whereby heat will be radiated from the floor to the tub thereabove. The fuel is preferably introduced into the combustion space beneath the floor by means of two groups of burners 50 arranged in the side 55 walls of the furnace. The two groups of burners are shown as arranged in staggered relation, see Fig. 2, the individual burners being so disposed that there is a floor opening 40 between any two adjacent burners. 60 By arranging the burners as indicated the burning gases from one group of burners tend to flow out through the openings 40 at the far side of the combustion chamber and the burning gases from the other group tend 65 to flow out through the other group of open-

ings 40 as will now be readily understood. However, the burning gases are not confined to any particular path of flow but may flow freely beneath the entire floor inasmuch as the floor is supported on pillars 38 70 which rise from the base 10 in more or less regular geometric relation as will be readily apparent by reference to Fig. 2.

The outer side walls 12 of the furnace are provided with cut-out portions or pockets 75 52 within which the burners 50 are disposed (see Fig. 1). Gas is supplied to the burners through suitable pipes 54 and preheated air for mixing with the gas is supplied through suitable pipes 56 which are supplied with 80 air from pipes 58 leading from the recuperator 48, the air to be heated in the recuperator being entered thereinto by way of a conduit 60 at the top of the recuperator.

The recuperator is preferably composed of 85 a plurality of metal conduits 62 so arranged so as to form a circuitous path for the air to be heated and to provide passages between and around the same for the hot gases which pass out of the heating chamber on their 90 way to the stack (not shown).

The floor of the heating chamber is provided with a pair of raised tracks 64 on which the tub to be heated may be supported in spaced relation to the floor during the 95 enameling operation. The bath tub to be heated is shown in dotted lines in Fig. 1 and is indicated by reference letter B. It will be noted that the heating chamber is considerably wider than the bath tub thus insuring a 100 uniform temperature around the entire tub.

By arranging the side walls of the heating chamber so that they shall be substantially parallel with the adjacent side walls of the tub, the amount of heat radiated to the tub 105 side walls from the chamber walls is substantially uniform through the entire area of the tub side walls. Moreover, by inclining the chamber side walls as stated, the hot gases entering the heating chamber through the 110 floor ports have a free unrestricted flow path between the adjacent chamber wall and tub wall,—a feature which serves to prevent concentration of the hot gases along the rolled over edge of the tub with consequent overheating of such edge. Another important result effected by having the chamber side walls inclined is that the hot gases entering the chamber are more readily deflected downwardly into the tub upon striking the arched 115 roof. Thorough circulation of the hot gases is therefore obtained with resultant uniformity of temperature throughout the entire chamber.

One serious drawback to direct-fired enameling furnaces as heretofore proposed has 125 been that particles of brick and the like would become dislodged from the chamber roof and side walls and fall into tub with consequent blemishing of the enamel. In the 130

present invention this difficulty is overcome by glazing the roof and side walls of the heating chamber with a suitable glaze before the furnace is put into use for enameling operations. The glazed walls of the chamber incidentally serve to permit better reflection and deflection of heat and hot gases into and against the tub. In order to minimize the entry of dust into the heating chamber from the operation of the heating chamber door, the door as previously explained is arranged to open downwardly instead of upwardly as is customary in ordinary furnace construction.

15 The fuel gas used in firing the furnace is preferably the same kind of gas as is supplied for household use in cities. This gas is clean and is admirably adapted for use in firing the furnace of the present invention.

20 The gas-air mixture should be such that more than sufficient air for theoretically complete combustion is supplied. By supplying an excess of air all tendency for soot to form is entirely obviated.

25 The present invention offers a furnace which may be built and maintained at a minimum of expense as compared with enameling furnaces now in use and enables the production of enameled bath tubs of first 30 quality at a minimum cost. Furthermore by providing the heating chamber with inclined side walls and heating the chamber in the manner indicated it has been found that the enamel operation can be completed with less 35 rehandling of the bath tub than is found necessary in the conventional type of enamel furnaces. The improved furnace has the further advantage of being easily operated on account of the fact that fuel for heating 40 the same has a substantially constant composition at all times.

What is claimed is:

1. In a furnace for enameling bath tubs, the combination of a heating chamber having its side walls inclined upwardly and outwardly from the floor thereof, the floor having a series of ports extending lengthwise of and adjacent to said walls, and means for supplying hot gases to the interior of said 50 chamber through said floor ports.

2. In a furnace for enameling bath tubs, the combination of a heating chamber having its side walls inclined upwardly and outwardly from the floor thereof, the floor having a series of ports extending lengthwise of and adjacent to said walls, means for heating said floor from beneath, and means for supplying hot gases to the interior of said chamber through said floor ports.

60 3. In a furnace for enameling bath tubs, the combination of a heating chamber having its side walls inclined upwardly and outwardly from the floor thereof, the floor having a series of ports extending lengthwise of and adjacent to said walls, means for

supplying hot gases to the interior of said chamber through said floor ports, and the roof of the heating chamber having a series of ports extending lengthwise of the chamber midway the sidewalls thereof and 70 through which roof ports the hot gases entered into the heating chamber may leave the chamber.

4. In a furnace for enameling bath tubs, the combination of a heating chamber having its side walls inclined upwardly and outwardly from the floor thereof, a plurality of combustion chambers of which said floor constitutes the roof, said floor having a series of ports extending lengthwise of and adjacent to said side walls and through which floor ports the combusted gases formed in the combustion chambers may flow into the heating chambers.

5. In a furnace for enameling bath tubs, the combination of a heating chamber having its side walls inclined upwardly and outwardly from the floor thereof, a plurality of combustion chambers of which said floor constitutes the roof, said floor having a series of ports extending lengthwise of and adjacent to said side walls and through which floor ports the hot products of combustion formed in the combustion chambers may flow into the heating chamber, and the roof of the heating chamber having a row of ports extending from one end of the chamber to the other through which the combustion products entered into the chamber may leave.

6. In a furnace for enameling bath tubs, a heating chamber having upwardly diverging side walls, a false floor in said chamber, said floor having openings extending along said side walls, means for burning fluid fuel beneath said floor for heating the latter throughout its area, said floor openings serving as passages for the entrance of the combustion gases into the heating chamber, an arched roof extending between said side walls and having a row of openings extending lengthwise thereof midway the side walls and through which openings the gases may leave the chamber, and means for regulating the size of the individual roof openings.

7. In a furnace for enameling bath tubs, a heating chamber having upwardly diverging side walls, a flat floor extending between said walls and having openings therein alongside said walls, a series of fluid fuel burners disposed beneath the floor between the floor openings, said openings serving as passages through which the combustion gases may enter said chamber, and means in the roof of the chamber for regulating the outflow of said gases from the said chamber.

8. In a furnace for enameling bath tubs, a heating chamber adapted to be heated by the burning of combustible gases there-

neath and means for introducing the combusted gases into the chamber along the base of opposite side walls of the chamber.

9. In an enameling furnace, a heating chamber having its interior walls initially provided with a refractory glaze.

10. The method of preparing the interior

of a furnace for enameling operations which comprises applying a glaze to the interior walls of the furnace before the furnace is used for enameling operations.

In testimony whereof I affix my signature.

FORREST W. MANKER.
